INSTRUMENT CARRIER

Albert R. Casavant, Box 1124,
Chattanooga, Tenn. 37401

Filed Mar. 24, 1971, Ser. No. 127,863

Term of patent 14 years

Int. Cl. D3—99

U.S. Cl. D87—1

FIG. 1

FIG. 3

FIG. 4

FIG. 2

FIG. 1 is a front perspective view of an instrument carrier showing my new design;

FIG. 2 is a rear elevational view thereof;

FIG. 3 is a top plan view of the instrument carrier of FIG. 2; and

FIG. 4 is a side elevational view of the instrument carrier.

I claim:

The ornamental design for an instrument carrier, as shown.
